UNITED STATES PATENT OFFICE.

CLARENCE E. MCKINSEY, OF CLEVELAND, OHIO.

PRINTING PRESS.

Application filed May 9, 1924. Serial No. 711,989.

To all whom it may concern:

Be it known that I, CLARENCE E. MCKINSEY, a citizen of the United States, residing at Cleveland, in the county of Cuyahoga and State of Ohio, have invented a certain new and useful Improvement in Printing Presses, of which the following is a full, clear, and exact description.

This invention relates to printing presses, and particularly to reciprocating flat bed cylinder or platen machines commonly known as flat bed printing presses.

One of the objects of the invention is to provide an improved type of interrupter to prevent the impression cylinder or platen from being lowered onto the printing form in the event of failure of the sheet feeding mechanism, i. e. in the event no sheet is fed between the printing form and the impression cylinder.

A further object is to control the degree of pressure between the printing form and impression cylinder so as to protect the printing form from injury in the event two or more sheets feed through the machine at the same time, or in case a torn or wrinkled sheet passes through the machine.

A further object is to provide improved mechanism for operating the sheet stop or obstruction device and the feed roll which cause the sheets to pass through the machine between the impression cylinder and printing form.

A still further object is to improve and simplify the means for bringing about adjustment of the relative position of the printing form and the sheet at the instant that the printing takes place, i. e. to adjust the position of the printed matter on the sheet.

The above and other objects are attained by my invention which may be here briefly summarized as consisting in certain novel details of construction, and combinations and arrangements of parts which will be described in the specification and set forth in the appended claims.

In the accompanying sheets of drawings wherein I have shown an embodiment of the invention which operates with high efficiency, Fig. 1 is a side view of a portion of a press of the flat bed type illustrating particularly the interrupter and pressure controlling means for the impression cylinder, omitting, however, many details of the

press not essential to an understanding of the invention; Fig. 2 is a longitudinal sectional view through a portion of the press illustrating particularly the reciprocating bed and certain other parts associated therewith substantially along the line 2-2 of Fig. 3, looking in the direction indicated by the arrows; Fig. 3 is a transverse sectional view, the section being taken substantially along the line 3-3 of Fig. 2, looking in the direction indicated by the arrows; Fig. 4 is a side view of part of the mechanism of the press looking toward the opposite side to that illustrated in Fig. 1, this view illustrating as does Fig. 1, a portion of the impression roll actuating means and part of the mechanism utilized in actuating the sheet stop and upper feed roll; Fig. 5 is a detached perspective view showing a detector finger which through associated parts controls the mechanism for shifting the impression cylinder so as to prevent the lowering of the latter in the event of failure of the feed mechanism to feed a sheet through the press; Fig. 6 is an enlarged detail sectional view showing a portion of the impression roll shifting mechanism, and particularly that part through which the pressure between the impression roll and printing form is controlled; Fig. 7 is a similar view of a portion of the mechanism utilized in shifting the sheet stop and feed roll; and Fig. 8 is a detail sectional view substantially along the line 8-8 of Fig. 1.

Referring now to the drawings, 10 represents the frame of the press along which is reciprocated in the usual manner the reciprocating bed 11 constituting what is termed in the claims the printing member and carrying the printing form which I have indicated somewhat conventionally at 12. I have not deemed it necessary to show the mechanism for shifting the bed 11 back and forth, as any suitable means common in machines of this type may be employed.

The inking of the printing form can be accomplished in any suitable way, but in the drawings I have shown at 13 a series of form inking rollers which can be actuated in the usual or any desired manner. At 14 I have shown the impression cylinder or platen roller, this roller being rotatably mounted on a shaft 15, which in turn is supported in block bearings 16 slidably ver-

tically in vertical guideways 17 in the opposite sides of the frame 10. It is in the mechanism for actuating this impression cylinder, i. e. for moving it downward when 5 the sheets on which the printing is done are fed in proper order, and for interrupting or preventing the downward movement in the event of failure of the feed in proper order, as well as for controlling the pressure be- 10 tween this cylinder and the printing form that important features of my invention re-side. This mechanism will be explained presently.

Referring again to the general descrip- 15 tion of the machine, the sheets are fed between a stationary upper feed plate 18 and a stationary lower feed plate 19. They may be fed by hand or otherwise between these plates, and when thus fed are adapted to 20 temporarily come against a sheet stop 20 which extends across the space between the feed plates and when lifted allows the sheet to pass. This sheet stop is secured to a rock shaft 21 which is journaled in the side 25 members of the frame and is actuated in a manner hereinafter explained.

The sheets are fed into the press by the action of two feed rolls including a lower roll 22 which is usually a steel roll, and an 30 upper rotatable roll 23 which is usually a rubber friction roll, the latter being mov- ably supported and being lowered into co-acting feeding relation with the lower roll so as to feed the sheet coincidently with 35 the lifting of the stop 20. The upper feed roll 23 is mounted on a shaft 21 which is supported at opposite ends in the arms 24 of a rock shaft 25 which is actuated, as 40 hereinafter described, to raise and lower the upper feed roll.

The impression cylinder 14 and upper feed roll 23 may be rotated in any suitable way, but preferably by a rack which moves 45 with the reciprocating bed, the rack being shown in section at 26 in Fig. 3. I have not deemed it necessary to illustrate, except conventionally, the trains of gears which 50 rotate these parts, as the particular rotating means for either the impression cylinder or feed roll per se forms no part of the present invention, but preferably the impression cylinder 14 has fixed to it a gear 14^a (see Fig. 8) which meshes with a gear 14^b meshing with a gear 14^c in turn engaged by the 55 rack 26, the gears 14^b and 14^c, which are shown by dotted lines in Fig. 1, being sup- ported on one of the side members of frame 10. The length of the teeth of gears 14^a and 14^b is such that the driving relationship 60 between the gears is not disturbed by the vertical movement which is given to the impression cylinder.

To drive the feed roll 23 I prefer to pro- 65 vide on shaft 21 a gear 27 as shown in Fig. 3, which meshes with a gear 28 shown in the

same figure, this gear being loose on rock shaft 25 and being engaged and rotated by gear 14^a on the impression cylinder 14, this driving relation being indicated by dotted lines in Fig. 1.

I will now describe the mechanism for raising and lowering the impression cylinder in predetermined timed relation with the movements of the reciprocating type form. Before describing the construction 70 and operation of this mechanism, it might be stated that assuming the sheets are fed in proper order, or at the proper rate in between the upper and lower feed plates, the impression cylinder is pulled down near 80 the beginning of the forward stroke of the reciprocating bed so as to press the sheet down against the printing form as the bed moves forwardly, and is lifted near the end of the forward stroke and is retained or held in elevated position until the early 85 part of the next forward movement of the bed.

The mechanism for thus actuating the impression cylinder includes two links or arms 29, which at their upper ends receive the ends of the shaft 15 on which the impression cylinder is rotatably mounted, these links extending downward a suitable distance along the opposite side members of the stationary frame 10. At their lower ends these links are connected to lever arms 30 secured to the forward ends of two rock shafts 31 which are supported in bearings 32 on opposite sides of the frame 10, one 95 of these rock shafts being shown in Fig. 1, and that on the opposite side of the machine being shown in Fig. 4. The rear ends of these rock shafts are provided with lever arms 33, each connected to a link composed of two parts 34 and 35 connected by a flexible coupling 36. It is to be understood that the mechanism so far described is duplicated on both sides of the machine. The lower link member on the side opposite to 100 that illustrated in Fig. 1, i. e. the lower link member 35 shown in Fig. 4 is connected by a lever arm 37 to a rock shaft 38 which is supported in bearings on the frame 10 and extends horizontally from one side of the machine to the other. The end of the rock shaft 38 shown in Fig. 1, which is the end opposite to that shown in Fig. 4, is provided with a lever arm 39 which is connected to a vertically movable slide 40 which is guided 110 for vertical movement in a housing 41, best shown in Fig. 1. The lower part 35 of the two-part link connected by the flexible coupling on the same side of the machine as the slide 40, is connected direct to the slide, 115 as illustrated in Fig. 1.

It will be seen that when the slide 40 is moved up and down, similar rocking movements are imparted to both horizontal rock shafts 31 and to opposite ends of the im- 120

pression cylinder, the movement of the slide being transmitted by the link composed of the two parts 34 and 35 and the flexible coupling 36, direct to one rock shaft 5 31, and the movement being transmitted to the rock shaft on the opposite side through the horizontal transverse rock shaft 38.

In Fig. 6 I have shown a detail of one of the two flexible couplings, each connecting 10 together the two parts 34 and 35 of the two two-part links. By referring to this figure it will be noted that the upper part 34 of the link is screwed into a plug 36^b which in turn is screwed into the top of a cylinder 36^b enclosing a coil spring 36^c. The lower member or part 35 of the link extends freely 15 through an adjustable plug 36^d screwed into the lower end of the cylinder and through the spring 36^c, the upper end being provided 20 with a shoulder in the form of an annular flange 36^e. The spring 36^c is between this shoulder 36^e and the lower plug 36^d. It will be seen, therefore, that when the slide 40 is pulled downward, causing the lower parts 25 or members 35 of the two-part links to be pulled downward, this downward movement is exerted on the springs 36^c and movement is transmitted by the springs to the cylinders 36^b and to the upper members or parts 30 34 of the two two-part links, causing both rock shafts 31 to be rocked in a direction such as to pull the impression cylinder downward to proper position with respect to the printing form. The parts of the flexible 35 couplings are so adjusted that with a single sheet between the printing form and impression roller, the latter will exert the requisite pressure onto the sheet and onto the printing form, but in the event that 40 there are two or more sheets between the impression cylinder and printing form, or a single wrinkled or crumpled sheet, the springs 36^c allow the impression cylinder to yield upward so as to prevent the face of the type or plates of the printing form being 45 injured by excessive pressure which would otherwise exist.

In practice the springs of the flexible couplings 36 need not be adjusted to accommodate sheets which vary in thickness within given limits. When once the springs are adjusted to cause the impression roller to exert the requisite degree of pressure for sheets of a given minimum thickness, the adjustment thus given is adapted for other thicknesses up to a certain maximum thickness, the springs yielding to a greater extent for the relatively thick sheets without causing any injury to the type or plates in the type form. When, however, it is desired to run through the press sheets which exceed the maximum referred to, it is only necessary to adjust the plugs 36^d at the lower ends of the cylinders, the plugs being lowered to accommodate the increased thick-

ness so as to increase the effective length and the elasticity or give of the springs. When once the plug at the lower end of a coupling is adjusted, it can be locked in that position against accidental displacement by means of 70 a lock nut 36^f which is screwed onto the shank of the plug and is adapted to be tightened up against the bottom of the cylinder 36^d. Both the head of the plug 36^d and the lock nut 36^f are provided with openings to 75 accommodate a spanner wrench or other suitable device for adjusting these parts.

The slide 40 is adapted to be moved up and down by a second slide 42, whose upper end is received in a slot in the lower end of 80 slide 40 and is adapted to be connected to and disconnected therefrom, as will be explained. Slide 42 is provided at its lower end with a roller 43 which is engaged in a cam groove 44 on the inner side of a cam 85 member 45 mounted on a shaft 46 which is rotated by the same motor or motive means which operates the reciprocating bed, and is driven at the proper speed or in proper relation with the other parts of the press that 90 at each revolution the impression cylinder is pulled downward to proper position with respect to the reciprocating type form, and then elevated. The shape and timing of the cam groove 44 are, of course, such that the 95 impression roller is brought downward and then elevated at the proper instants in each cycle of printing operations.

In the above description it is assumed that the feed of sheets on which the printing is to be done takes place properly. In that event, the up and down movement of the lower slide 42 is transmitted to the upper slide 40 and from the latter, through the mechanism described above, to the impression roller. 100 However, in case a sheet is not fed into the press at the beginning of the forward stroke of the bed, the upper slide 40 is unlatched from the lower slide 42 and is held stationary, thus preventing the downward movement of the impression cylinder, the lower slide then reciprocating freely with reference to the upper slide. 105

The two slides are adapted to be locked together by a locking pin or bolt 47 which 110 extends freely through one side of the housing 41 into an opening in slide 40 and is adapted to be inserted into a similar opening of slide 42 when the two openings register or are in alignment. Similarly, the upper slide 40 is adapted to be locked to the housing by a locking pin or bolt 48 which has a sliding movement in an opening of the housing and is adapted to be extended into an opening of slide 40 when the two openings 115 are in registration. The outer ends of these two locking pins are pivotally connected respectively to the upper and lower ends of a lever 49, pivoted intermediate its ends on a supporting projection 50 of the hous- 120

125

130

ing 41, as clearly shown in Fig. 1. Obviously the construction is such that the locking pins are moved simultaneously in opposite directions so that when one is moved to locking position the other is moved to unlocking position.

The locking and unlocking means just described for the two slides 40 and 42 forms a part of my improved interrupter employing a sheet detector finger 51, shown in Figs. 2, 3 and 5. This detector finger is carried by a rock shaft 52 which extends between the two side members of the frame 10, and is located between the rock shaft 10, and is located between the rock shaft 15 21 carrying the sheet stop 20 and the upper feed roll 23, as shown in Fig. 2. This detector finger is secured to a block 53 fastened to the rock shaft, and it may be adjusted on the block by a set screw 54 and suitable lock 20 nut associated therewith. The finger is adapted to extend through openings in the upper and lower feed plates 18 and 19 shown in Fig. 2. Obviously, if a sheet is on the lower feed plate 19 the detector finger, if 25 free to move downward, will rest on the sheet, but if there is no sheet on the lower feed plate, it will swing downward through the opening in the plate. When this occurs, at or about the time the reciprocating 30 bed starts on its forward stroke, by the mechanism next to be described, the two lock pins 47 and 48 are actuated so as to disengage or unlock the lower slide 42 from the upper slide 40 and to lock the latter to the 35 housing.

This is accomplished by mechanism including an escapement finger 55, which is mounted on a portion of rock shaft 52 (which carries the detector finger) projecting laterally beyond one of the side members of the frame 10. This escapement finger has a notched lower end adapted when the escapement finger is in vertical position, shown by full lines in Fig. 1 and in Fig. 5, 40 to engage the pointed or wedge shaped upper end of a rod 56 which extends downward alongside the frame 10 and is connected to the rearwardly extending arm of a bell-crank 57. When the rod 56 is moved upwardly it compresses a spring 58 arranged between a shoulder 59 on the rod and a bracket 60 secured to the frame 10, as shown in Fig. 1, this bracket serving as a guide for the rod, as will be apparent from Figs. 45 55 1 and 5. Extending alongside the rod 56 is a second rod 61, which at its lower end is connected to the same arm of bell-crank 57, and which at its upper end is connected to an escapement actuator 62, loosely mounted 60 on the laterally projecting end of rock shaft 52. This actuator has a shoulder 62^a, against which is normally pressed a pin 63, projecting laterally from the escapement finger 55, the outer end of this pin being fixed in 65 a short arm 64, mounted on a center 65, ar-

ranged coaxially with rock shaft 52, which center is carried by a bracket 66 secured to a side member of the frame 10, as clearly shown in Fig. 5. The escapement finger 55, pin 63 and arm 64 constitute in effect 70 one member secured to rock shaft 52. Pin 63 is pressed against the shoulder 62^a of the escapement actuator 62 by a leaf spring 67, which is best shown at the left hand side of Fig. 3, and a portion being shown 75 in Fig. 5, this leaf spring being supported on bracket 66, and bearing against arm 64.

It will be seen from the above, that when rods 56 and 61 move downwardly (under the action of spring 58) the shoulder 62^a 80 of actuator 62, which is connected to rod 61, will swing the escapement finger in a counter-clockwise direction as the same is viewed in Figs. 1 and 5. This will elevate the detector finger and permit a sheet to slide 85 down between the feed plates 18 and 19. Likewise, it will be seen that when rods 56 and 61 move upward, the shoulder 62^a of actuator 62 moves back or away from pin 63, allowing it and the escapement finger to swing downward by gravity and by the action of spring 67. When the detector finger swings downward, the rock shaft 52 is turned, carrying with it the detector 90 finger 51. When the finger 51 moves downward, if there is a sheet on the lower feed plate, the finger engages the sheet and is stopped, as is also the rock shaft and escapement finger, the latter then being to one 95 side of its vertical position as shown by dotted lines in Fig. 1. On the other hand, if there is no sheet on the lower feed plate, the detector finger drops through the hole in the lower feed plate, and the escapement finger continues its movement to vertical position. 100 When this occurs, rod 56 is moving upwardly, and at the instant that the escapement finger reaches vertical position it is engaged by the wedge-shaped upper end of rod 56 and the upward movement of this 105 rod and of the associated rod 61 is stopped.

The action of the detector finger and of the above described parts cooperating therewith is utilized in controlling the locking and unlocking of the two slides 42 and 40 110 by the following means.

A link 68 is connected at one end to a downwardly extending arm of the bell-crank 57, to the horizontal rearwardly extending arm of which the rods 56 and 61 are connected as described above. Pivotedly connected to the forward end of link 68 is a lever 69 arranged at the side of frame 10. The lever is connected to the link at its lower end, and a short distance above its lower end it is pivotally connected to a slide 70 mounted for horizontal movement in a housing 71 on the side of the frame 10, and provided at its forward end with a roller 72 125 adapted to be engaged by a cam 73 on the 130

periphery of cam member 45. Near its upper end the lever 69 is connected to a link 74, the forward end of which is connected to an extension of locking pin 47, which, as already described, is utilized to lock together the two slides 42 and 40. The upper end of lever 69 is capable of a certain sliding movement between the side of the frame 10 and a guide clip 76. A spring 77, which is connected to the lever near its upper end and to the side of the frame 10 normally restrains the upper end of the lever from movement toward the left, as the same is viewed in Fig. 1, under the action of cam 73.

15 The operation of the interrupter mechanism is as follows: When the sheets feed in regular order through the press so that the upward movement of rod 56 is not obstructed by the escapement finger 55, cam 20 73 by its action on roller 72 and slide 70 rocks lever 69 without imparting any movement to the locking pins 47 and 48, the lever 69 then rocking about a point 78, which is the pivotal connection between lever 69 and link 70. That is to say, when cam 73 engages the roller it moves the lower end of lever 69 to the left as the same is viewed in Fig. 1, allowing a full swing to bell crank 57, and the normal upward movement of rods 56 and 61. Then when the cam 30 73 leaves the roller 72 the lever 69 again swings inward to the right, pivoting, as stated above, about point 78. This movement of lever 69 imparts no movement to the locking pins 35 and as long as the feed of sheets takes place in regular and proper order the locking pin 47 remains in locking position, locking slide 42 to slide 40, and locking pin 48 is retracted, with the result that the impression 40 roller is at the proper instant in each cycle moved downward to cause the printing impression to be imparted to the sheet, and is then elevated and held in elevated position until the next printing cycle.

45 If, however, a sheet fails to feed into the press for any reason, this free swinging movement of lever 69 about point 78 is prevented by reason of the fact that the detector finger drops through the hole in the 50 lower feed plate, the escapement finger comes into alignment with rod 56, or to the position shown by full lines in Fig. 1, and the upward movement of rod 56 is stopped. This, of course, stops the movement of bell-crank 55 55 57, with the result that link 68 obstructs the swinging movement to the left (as viewed in Fig. 1) of the lower end of lever 69, in consequence of which, the action of cam 73 on the roller 72 is to now swing the lever 69 about point 79, or about its lower end, causing the upper end of the lever 69 to swing to the left so as to reverse the positions of the locking pins 47 and 48. That is to say, locking pin 47 is withdrawn so as to release or 60 unlock slide 42 from slide 40, and locking pin 48 is moved inwardly so as to lock slide 40 to housing 41. When this occurs, slide 42 has a free or inactive stroke, and slide 40 and the mechanism connecting it to opposite ends of the impression cylinder are held 70 stationary, preventing the lowering of the impression cylinder.

75 The cam 73 is, of course, so designed that it operates in proper timed relationship with the other parts to cause the locking pins 47 and 48 to be actuated when the openings in which these pins are adapted to slide are in registration, and to cause the interrupter as a whole to function as described, i. e. to cause the impression cylinder to be lowered 80 only when the sheets are fed in proper order into the press, and to hold it in elevated position during each cycle of the press that a sheet is not fed therein.

85 I will next described the important means which I have provided for bringing about an adjustment of the position of the printed matter on the sheet. Heretofore, in all presses of which I am aware this has been accomplished with the expenditure of considerable 90 time and labor by adjusting the position of the type form on the cylinder or reciprocating bed as the case may be. In my improved machine, this adjustment is accomplished in an easy and simple manner, not by adjusting the position of the printing form, but by adjusting the time in the cycle of operations that the sheet stop or obstructing device is lifted and the upper feed roll is lowered to feeding position on the lower feed roll. The 95 adjustment in this manner is made possible by a novel and effective mechanism for actuating the sheet stop and feed roll, which I will now describe.

100 I provide on the reciprocating bed for the actuation of the sheet stop and upper feed roll, an actuating member through which the adjustment is made. This actuating member is preferably in the form of a cam or cam rail 80 (see Figs. 2 and 3) which is 105 secured in this instance to the bottom of the reciprocating bed 11 which carries the printing form 12. As clearly shown in Fig. 2, this cam rail which extends a considerable distance along the bottom of the bed, and 110 preferably extends rearwardly beyond the same, is provided on its lower face, which is the working face, with tapered end portions 80^a, and with a straight horizontal portion between the two tapered portions. This 115 cam rail is secured to the lower side of the bed, and provision is made for adjusting it lengthwise of the bed whenever, and to the extent desired. It can be secured to the bed and adjusted in different ways, but in this instance it is held to cross ribs 11^a of the bed (see particularly Fig. 2) by screws 81 extending through slots 80^b in a horizontal flange 80^c (see Fig. 3) projecting laterally 120 from the vertical portion whose lower face is 125 130

the working face of the cam rail as stated above. The cam rail can be moved lengthwise of the bed without adjusting the screws 81 by means of an adjusting screw 82 arranged at the rear end of the bed, as clearly shown in Fig. 2. This adjusting screw is connected to a lug or boss 80^a, projecting upwardly and laterally from the cam rail, and it has threaded engagement with the rear portion 10 of the bed. A lock nut 83 is provided to hold the adjusting screw, and hence the cam rail, in any desired position. By this means the cam rail can be given a considerable range of adjustment, the total adjustment 15 depending upon the length of the slots 80^b accommodating the screws 81, and the length of the adjusting screw and the length of these parts can be made anything desired to provide for the maximum adjustment necessary in practice.

The lower working face of the cam rail is engaged by a roller 84 carried at the upper end of an arm 85, which at its lower end is pivoted on a pin 86 carried by a vertically 25 movable slide 87, supported within the frame 10 and guided for vertical movement by a guide pin 88, clearly shown in Fig. 3. The arm 85 is normally held up against the stop 87^a of slide 87 by means of a spring 89, shown in Figs. 2 and 3, this spring being connected to the arm and to a suitable part of the frame 10.

On the rearward stroke of the bed, that is to say, when the bed and cam rail are moving to the left, as viewed in Fig. 2, arm 85 swings away from the stop 87^a to substantially the full line position indicated in Fig. 2 without lowering slide 87 to any material extent. Near the end of the rearward stroke 35 the cam rail rides free of the roller due to the tapered portion shown at the right hand end of Fig. 2, whereupon the arm 85 assumes its normal vertical position against the stop. On the reverse stroke of the bed, 40 i. e. on its working stroke, the cam rail re-engages the roller 84, but the engagement of the cam rail while moving in the right hand direction as viewed in Fig. 2 simply depresses the arm 85 and slide 87, the arm 85 being 45 then maintained in vertical position against the stop 87^a. Obviously, the time of the downward stroke of the arm and slide depends wholly upon the position of the cam rail on the bed, the downward movement 50 taking place sooner in the cycle if the rail is adjusted in a forward or inward direction, and taking place later in the cycle if it is adjusted in a rearward or outward direction.

When the slide is depressed as just stated, 55 it compresses a spring 90 arranged between the slide and a shelf 10^a on the frame 10. This spring serves to again elevate the slide, its upward movement being limited by a stop 91 carried by a shelf 10^b of the frame,

this stop being in the form of an adjustable screw which can be adjusted to vary the normal height of the arm and of the slide.

A portion of the slide 87 extends to one side of the frame 10 through an opening 70 therein, and the outer projecting end of the slide is connected to a link or rod 92 which in turn is connected to a similar rod 93 through the medium of a flexible coupling 94 (see Fig. 7). This coupling includes a cylinder 75 94^a into which both rods 92 and 93 extend. Rod 92 has at its upper end a head 94^b between which and the bottom of the cylinder is a coil spring 94^c which serves as a shock absorber when movement is transmitted to the upper rod 93, this spring being compressed when the rod 92 is pulled downward. The upward movement of rod 92 in the cylinder is limited by an adjustable stop 94^d. Rod 93 has threaded engagement with an 85 adjustable plug 94^e which is screwed into the upper end of cylinder 94^a, and which can be adjusted to raise or lower rod 93, and can be locked in position by a lock nut 94^f. The purpose of this adjustment is to compensate 90 for wear of the upper feed roll, the rod being lowered into the cylinder the desired amount to compensate for any given wear.

By reference to Fig. 1 it will be noted that 95 rod 93 is connected by a crank arm 95 to the rock shaft 25 which was referred to in the early part of this description, and which is provided with the arms 24 carrying shaft 21 on which the upper feed roll 23 is secured.

By reference to Fig. 4 it will be seen that 100 the opposite end of rock shaft 25 to the end shown in Fig. 1, is provided with a crank arm 96, and this is connected by a connecting rod 97 to a crank arm 98 which is secured to rock shaft 21 carrying the sheet 105 stop or obstructing device 20, as previously described. An adjustable connection is preferably provided between connecting rod 97 and crank arm 98, and this can be made in a simple way by extending a pin 98^a on the 110 crank arm 98 through a slot 97^a in the connecting rod, and by providing in the end of the connecting rod an adjustable screw 97^b, against which the pin 98^a bears. A spring 99 is preferably connected to an extension of 115 crank arm 98 and to a side member of the frame to constantly hold the pin 98^a against the adjustable screw 97^b and to eliminate vibration and chatter. Similarly a spring 100 may be employed to prevent vibration in 120 the upper feed roll when it is elevated, the spring 100 here shown, being connected to the lower arm of crank arm 96 and to a stationary pin on the side member of the frame 10.

It will be seen from the above, that the rock shaft operating the upper feed roll is connected to the rock shaft carrying the sheet stop or obstructing device so that both the feed roll and sheet stop move in unison,

the former downward to feeding position and the latter upward to allow the feed of the sheet into the press. Likewise it will be seen that the feed roll is lowered and 5 the sheet stop elevated, as just stated, through the action of cam rail 80, shortly after the bed starts on its forward or working stroke, and that the time in the cycle that the feed of the sheet begins, and therefore 10 the position of the printed matter on the sheet depends on the position that the cam rail occupies on the under side of the bed, which position can be easily adjusted, as already explained, and without requiring 15 expert skill which heretofore has been necessary when adjustment of the type form has been required.

When the sheet is fed into the press, the type form is in position to receive it, and 20 it is carried forwardly by the action of the type form and of the rotating impression cylinder, this forward movement being assisted by the action of the feed rolls 22 and 25 23, until the sheet passes the latter.

25 As the sheet passes through the press it is guided forwardly and upwardly by a pair of guide fingers 101 which engage the marginal portions of the sheet. From these 30 guide fingers the sheet passes up onto suitable conveying means such as traveling tapes, not shown, and commonly employed to carry the printed sheet onto the delivery table. Guide fingers to guide the sheet in this manner are common on printing 35 presses, but in all prior presses of which I am aware, these guide fingers are stationary, though, of course, laterally adjustable to accommodate sheets of different widths, and generally in presses of the type herein illustrated they move with the impression cylinder.

In my improved machine these guide fingers are supported independently of the impression cylinder, and they are movably 40 supported so as to bring friction rollers 102, one carried by each guide finger, and one only being shown in Fig. 2, into engagement with the impression cylinder when a sheet is passing through the press, it being understood that the function of these rollers 45 102 is to complete the feed of the sheet onto the tapes or other traveling conveying means after the printing form has passed beyond the impression cylinder. In my present construction the rear ends of the 50 guide fingers 101 rest on the forward end of the lower feed plate 19, and at their forward ends they are pivotally connected to crank arms 103 on a rock shaft 104 mounted in the side members of the frame, as best shown in Fig. 2. This rock shaft is 55 rocked at the proper instant to cause the crank arms 103 to bring the small friction rollers 102 into engagement with the surface of the impression cylinder so as to be

rotated thereby, and preferably this rock shaft is coupled to the mechanism which raises and lowers the impression cylinder. This is accomplished in this instance by utilizing for this purpose one of the horizontal rock shafts 31 shown in Fig. 4. This rock shaft is provided between its ends with a collar 105 carrying a short inwardly extending arm 106 which is connected by a link or connecting rod 107 to a crank arm 108 on rock shaft 104. 70 75

By the described mechanism, when the impression cylinder is lowered to coact with the printing form, rock shaft 104 is rocked so as to bring friction rollers 102 into contact with the impression cylinder. When the impression cylinder is lifted, the rollers 102 and impression cylinder move out of engagement with each other. Because of the fact that the rollers 102 and impression 80 85 cylinder 14 are in engagement only during the brief period that the sheet is being fed through the press, wear incident to the engagement of these parts is reduced to a minimum. 90

By having the guide fingers and friction rollers 102 actuated, in the manner described, from the mechanism which operates the impression cylinder, there is a peculiar and effective but important result obtained, not obtained if the guide fingers are actuated by some other moving part of the press, for the reason that the actual downward movement imparted to the impression cylinder depends upon the thickness of the sheet, or other material on which the printing is done. That is to say, the distance that the impression cylinder moves downward is inversely proportionate to the thickness of the sheet. Therefore, the movement of the friction rollers 102 toward the impression cylinder varies inversely as the thickness of the sheet increases, thus providing less pressure between these friction rollers, and the impression cylinder for the thicker sheets, as 100 105 is desired to prevent undue flexing and possible permanent bending of the guide fingers when thicker material is encountered. This obviates the necessity of frequently repairing or reshaping the guide fingers as has 110 115 heretofore been necessary.

In addition to this automatic variation of the movement of the friction rollers 102 and guide fingers 101, the normal position of these parts can be varied or adjusted at any 120 time by angularly adjusting the position of collar 105 on the rock shaft 31 which supports it. This adjustment is taken advantage of at times when the sheets or blanks fed through the press vary radically in 125 thickness.

In describing the construction of the press embodying my improvements, I have at the same time described the operation of the parts, and it is believed that the operation 130

will be readily understood without any further description.

I have illustrated in the drawings and have described only the preferred embodiment which has proven by practice and extensive use to be very effective and to have all the advantages described herein, and though I have shown only one embodiment, I do not wish to be confined to the precise 10 construction illustrated, nor to the type of press shown, but aim in my claims to cover all modifications which do not involve a departure from the spirit and scope of my invention.

15 Having described my invention, I claim:

1. In a printing press, a movable printing member adapted to be provided with a printing form, a movable impression member, and means for moving one of said members toward and from the other, said means including a power-operated actuating device and a yieldable element between it and the member to be moved whereby said members may be spaced different distances apart during 25 the printing operations to compensate for different thicknesses of sheets or material fed between said members.

2. In a printing press, a movable printing member adapted to be provided with a printing form, a movable impression member adapted to cooperate therewith, and means for moving said impression member toward and away from the printing member, said means including a power-operated 30 actuating device and yieldable means between it and the impression member which permits the impression member to be spaced different distances from the printing member during the printing operation to provide for different thicknesses or numbers of 40 sheets or blanks fed between said members.

3. In a printing press, a movable printing member adapted to be provided with a printing form, an impression member movable toward and from the printing member, and means including a power-operated member for pulling the impression member down into coacting relation with the printing member, said means permitting the space 45 between the printing member and impression member to vary in accordance with the thickness of a sheet or blank or the number thereof passing between said members during the printing operation.

55 4. In a printing press, a movable printing member adapted to be provided with a printing form, an impression member movable toward and from the printing member, and power-operated means for pulling 60 the impression member down into coacting relation with the printing member to compensate for variations in thickness of the material fed between the members, said means comprising parts connected by a 65 yieldable coupling.

5. In a printing press, a movable printing member adapted to be provided with a printing form, an impression member movable toward and from the printing member, and power-operated means for pulling the impression member down into coacting relation with the printing member to compensate for variations in thickness of the material fed between the members, said means comprising parts connected by a compression spring.

6. In a printing press, a movable printing member adapted to be provided with a printing form, an impression member movable toward and from the printing member, and means for pulling the impression member down into coacting relation with the printing member to compensate for variations in thickness of the material fed between the members, said means comprising a power operated actuating member and a yieldable device between said actuating member and the impression member.

7. In a printing press, a movable printing member adapted to be provided with a printing form, an impression member movable toward and from the printing member, and means for pulling the impression member down into coacting relation with the printing member, said means comprising a power operated actuating member and means connecting said actuating member to opposite ends of the impression member and involving two yieldable devices whereby the impression member may yield to 100 compensate for variations in thickness of material fed between the members.

8. In a printing press, a reciprocating bed adapted to be provided with a printing form, an impression cylinder, means for rotating the cylinder, and means independent of the rotating means for moving the cylinder toward and away from the path of movement of the bed, said last mentioned means permitting the cylinder to 105 yield so as to vary the space between it and the printing form during the printing operations in accordance with the thickness of the material which receives the printing impression.

9. In a printing press, a reciprocating bed adapted to be provided with a printing form, an impression cylinder means for rotating the latter, and means independent of the rotating means for moving the impression cylinder toward and from the path of movement of the bed in proper timed relation with the reciprocating movements of the bed, said means including a power operated actuating member and means for automatically controlling the pressure of the impression member on the printing form as the material passing between the printing form and impression cylinder varies in thickness.

10. In a printing press, a movable printing member adapted to be provided with a printing form, a movable impression member adapted to cooperate therewith, and mechanism for moving one of said members toward and from the other, said mechanism including parts adapted to be latched together when the feed of blanks takes place in the proper order so as to form a movement transmitting connection with the said member and to be unlatched when the feed of blanks is interrupted so as to break the connection without affecting the movement of the other member.
15. In a printing press, a movable printing member adapted to be provided with a printing form, an impression cylinder, mechanism for moving the same toward and from the printing member, said mechanism having means for controlling the pressure of the impression member so as to prevent injury to the printing form when two or more blanks or a blank of increased thickness is between the printing and impression members, and means for automatically preventing the movement of the impression member toward the printing member on the failure of feed of blanks.
20. In a printing press, a movable printing member adapted to be provided with a printing form, a movable impression member adapted to be moved toward and from the printing member, mechanism for thus moving the impression member and including two parts adapted to be locked together and unlocked, and means comprising a detector finger operative upon the failure of the feed of blanks for controlling the locking and unlocking means.
25. In a printing press, a movable printing member, an impression member adapted to be moved toward and from the printing member, mechanism for thus moving the impression member and including a power operated device, means adapted to connect said device with the impression member and including two parts, and means for locking said parts together to complete a movement transmitting connection from said power operated device to the impression member and for unlocking them so as to break the movement transmitting connection, and means comprising a detector finger rendered operative by the failure of the feed of blanks for controlling said locking and unlocking means.
30. In a printing press, a movable printing member adapted to be provided with a printing form, an impression cylinder, mechanism for moving the same toward and from the printing member, said mechanism including a power operated member, a second member adapted to be actuated thereby, a locking device for locking said members together, a second locking device for locking said second device against movement, and means comprising a detector finger for controlling said locking devices.
35. In a printing press, a movable printing member adapted to be provided with a printing form, an impression cylinder, mechanism for moving the same toward and from the printing member, said mechanism including a power operated member, a second member adapted to be actuated thereby, a locking device for locking said members together, a second locking device for locking said second device against movement, and means comprising a detector finger for controlling said locking devices.
40. In a printing press, a movable printing member adapted to be provided with a printing form, an impression cylinder, mechanism for moving the same toward and from the printing member, said mechanism including a power operated member, a second member adapted to be actuated thereby, a locking device for locking said members together, a second locking device for locking said second device against movement, and means comprising a power operated member for actuating said locking devices, and means comprising a detector finger rendered effective by the failure of feed of blanks or forms for controlling said power actuated member.
45. In a printing press, a printing member adapted to be provided with a printing form, an impression cylinder, mechanism for moving the same toward and from the printing member, said mechanism having means for controlling the pressure of the impression member so as to prevent injury to the printing form when two or more blanks or a blank of increased thickness is between the printing and impression members, and means for automatically preventing the movement of the impression member toward the printing member on the failure of feed of blanks.
50. In a printing press, a movable printing member adapted to be provided with a printing form, an impression member, mechanism for moving said impression member toward and from the printing member or its path of movement, said mechanism having means for automatically varying the distance between the members as the thickness of material between the members is varied during the printing operations, and means for preventing the movement of the impression member toward the printing member on the failure of feed of sheets or blanks.
55. In a printing press, a movable printing member adapted to be provided with a printing form, an impression member cooperating therewith, a movable feeding device for feeding blanks between the printing and impression members, and means for varying the time that the feeding device operates in the cycle of operations to vary the position of the printed matter on the sheets.
60. In a printing press, a movable printing member adapted to be provided with a printing form, an impression member cooperating therewith, means comprising a movable feed roll for feeding blanks between the printing and impression members, means for intermittently actuating the feed roll, and means for varying the time of actuation of the feed roll in the printing cycle.
65. In a printing press, a movable printing member adapted to be provided with a printing form, an impression member cooperating therewith, means comprising a pair of cooperating feed rolls for feeding blanks between the printing and impression members, means for moving one of said feed rolls into coacting relation with the other to start the feed of a blank, and means for varying the time of the movement of said feed roll to vary the position of the printed matter on the blanks.
70. In a printing press, a printing member adapted to be provided with a printing

form, an impression member adapted to co-operate therewith, sheet feeding means, a sheet stop, means for actuating the sheet stop to permit the feed to take place, and 5 means for varying the time of operation of the sheet stop in the printing cycle.

21. In a printing press, a printing member adapted to be provided with a printing form, an impression member cooperating therewith, a movable sheet feeding device, 10 a movable sheet stop, means for shifting the feeding device and the stop to initiate the feed of a blank, and means for adjusting the time of operation in the printing 15 cycle of the movement of the feeding device and stop.

22. In a printing machine, a movable printing member adapted to be provided with a printing form, an impression member 20 cooperating therewith, a feed plate along which sheets are adapted to be fed one at a time into the press, a pair of actuating feed rolls, one movable toward and from the other, a sheet stop adapted to temporarily 25 obstruct the feed of each sheet, means for actuating the movable feed roll and the sheet stop to permit the sheet to be fed into the press, and means for varying the time of operation of said roll and stop to vary 30 the position of the printed matter on the sheet.

23. In a printing machine, a reciprocating bed adapted to be provided with a printing form, an impression cylinder adapted to 35 cooperate with the form, a feed plate along which sheets are adapted to be fed, a movable feed roll for initiating the feeding of the sheets, a sheet stop for temporarily obstructing the movement of each sheet, and 40 means operated by the reciprocation of the bed for actuating said feed roll and stop and including an adjustable member by which the time of actuation of the movable feed roll and stop occurs in the printing cycle.

45. 24. In a printing press, a reciprocating bed adapted to be provided with a printing form, an impression cylinder, a device for feeding sheets into the press, and means comprising an adjustable cam rail carried 50 by the bed for actuating said feeding device.

25. In a printing press, a movable printing member adapted to be provided with a printing form, an impression cylinder, means for feeding sheets into the press, a

movable sheet stop for temporarily obstructing the movement of the sheets, and means comprising an adjustable cam rail carried by the bed for actuating said stop. 55

26. In a printing press, a reciprocating bed adapted to be provided with a printing form, an impression cylinder, sheet feeding means including a movable member, a sheet stop, and means comprising an adjustable cam rail carried by the bed for actuating said feeding device and stop. 60

27. In a printing press, a reciprocating bed adapted to be provided with a printing form, an impression cylinder, a movable feed roll, a movable sheet stop, and means operated by the reciprocation of the bed 70 for operating the feed roll and stop and including a part adapted to be adjusted relative to the bed to vary the time of operation of said means in the printing cycle. 75

28. In a printing press, a movable printing member adapted to be provided with a printing form, a rotary impression cylinder movable toward and from the printing member, a feed roller, and means operating in timed relation with the movement of the impression cylinder for moving the feed roller into and out of engagement with the impression cylinder. 80

29. In a printing press, a printing member adapted to be provided with a printing form, a rotary impression cylinder movable toward and from the printing member, a sheet guide carrying a feed roller, and means for moving said guide so as to bring the roller into and out of engagement with the impression cylinder as the latter is moved toward and then away from the printing member. 85

30. In a printing press, a movable printing member adapted to be provided with a printing form, a rotary impression cylinder, mechanism for moving the impression cylinder toward and from the printing member, a guide strip carrying a feed roller, and means actuated by the said mechanism for moving the impression cylinder for actuating the guide strip so as to move the feed roller carried by it into and out of coacting relation with the impression cylinder. 90 100

In testimony whereof, I hereunto affix my signature. 105

CLARENCE E. MCKINSEY.
